F. E. BEST

PADLOCK

Filed Feb. 14, 1922

III. 1

Frank E. Best
Inventor

UNITED STATES PATENT OFFICE.

FRANK ELLISON BEST, OF SEATTLE, WASHINGTON, ASSIGNOR TO FRANK E. BEST, INC.,
OF SEATTLE, WASHINGTON, A CORPORATION OF WASHINGTON.

PADLOCK.

Application filed February 14, 1922. Serial No. 536,427.

To all whom it may concern:

Be it known that I, FRANK E. BEST, a citizen of the United States, residing at Seattle, in the county of King and State of Washington, have invented certain new and useful Improvements in Padlocks, of which the following is a specification.

This invention relates to padlocks and, more especially, to that type of padlocks having shackles arranged to be secured in various positions to the lock body by means of latch devices which are regulated by lock mechanism of the character illustrated and described in United States Patent No. 15 1,884,022 issued to me July 5, 1921.

The object of the invention, generally stated, is the perfecting of locks of this type to render the same more serviceable and convenient to use.

More specific objects and advantages to the invention will appear from the following description.

The invention consists in the novel construction, arrangement and adaptation of parts hereinafter described and claimed.

In the accompanying drawings,—

Figure 1 is a perspective view of a padlock embodying my invention. Fig. 2 is a longitudinal sectional view of the lock, the shackle being shown in side elevation. Fig. 3 is a transverse sectional view through 3—3 of Fig. 2, the core assembly containing the lock mechanism being omitted. Fig. 4 is a perspective view of the lock tumbler.

In said drawings, the reference numeral 5 represents the lock body comprising a tubular shell 6 into the ends of which are welded or otherwise integrally connected top and bottom walls 7 and 8 and in juxtaposition with blocks 9 and 10 which are disposed at opposite ends respectively of the shell chamber.

Adjacent to its opposite sides, the body is provided with apertures 11 and 12 extending entirely through said body to receive the legs 13 and 13¹ of a shackle 14. The shackle legs are provided along their inner sides with series of spaced notches 15 and 15¹.

Provided between blocks 9 and 10 in the

lock body is the housing, indicated by 16, 50 for a core assembly containing the lock mechanism which is or may be similar to the correspondingly designated assembly illustrated and explained in the patent above referred to.

The core assembly in the present invention is removable from the housing 16 through an opening 17, Figs. 1 and 3, in a side of the shell, said opening being closed by a face plate 18 whose outer surface is flush or co-extensive with the outer surface of the shell surrounding such opening. The core assembly, like in the aforesaid patented lock, is detachably secured in place by means of a "settable" key inserted in key-hole 19, Fig. 1, operating in a key-plug 20 to project a gate 21, Fig. 2, into or from its engaged relations with the core housing 16.

The key plug 20, when controlled by means of what is conventionally called a 70 "workable" key inserted in the keyhole 19, serves through the medium of the throw element 22 of the plug to regulate a tumbler 23 which constitutes the shackle fastener.

More particularly, this tumbler consists of 75 a bar 24 having a hook 25 at one end and an offset arm 26 at its other end as shown in Figs. 2 and 4.

The tumbler is located in a recess 27 of the block 9 and is mounted for oscillatory 80 movements by the provision of trunnion elements 24¹ which are journaled in pockets, such as 28, Fig. 2, provided for the respective trunnions in opposite sides of the recess 27.

29 represents a spring secured in a groove 30 of the wall 7 and acts resiliently against the tumbler to retain the tumbler-hook 25 in engagement with one of the notches in the adjacent shackle leg for coupling the shackle 90 to the body of the lock.

To disengage the tumbler from the shackle, the workable key is utilized to impart rotary movement to the plug 20 thereby causing the throw 22 to act through the medium of the arm 26 to effect the withdrawal of the hook 25 from its engagement with the shackle.

What I claim, is,—

In a padlock, the combination of the body, a shackle having parallel legs adapted to extend through holes provided therefor in said body, a core insertible in said body between the shackle legs, a tumbler engageable with either of said shackle legs selec-

tively, a core provided within the body, key actuated locking mechanism provided in said core for regulating said tumbler with respect to the shackle, and means for detachably securing the core within the housing.

FRANK ELLISON BEST.
